UNITED STATES PATENT OFFICE.

HARRY M. COULTER, OF SPRINGFIELD, MASSACHUSETTS.

CARBURETER.

1,125,069.

Specification of Letters Patent.

Patented Jan. 19, 1915.

Application filed January 31, 1914. Serial No. 815,659.

To all whom it may concern:

Be it known that I, HARRY M. COULTER, a citizen of the United States of America, residing at Springfield, in the county of 5 Hampden and State of Massachusetts, have invented certain new and useful Improvements in Carbureters, of which the following is a specification.

This invention relates to carbureters and 10 more particularly to devices for regulating the amount of fuel delivered thereto.

An object of the invention is to provide a carbureter with improved interconnecting means between the controlling mechanisms 15 for the air and the fuel. As the fuel supply is throttled, so also is the supply of air, since the controlling devices are made to operate in unison.

Another object is to provide simple mechanism 20 by means of which the supply of fuel can be quickly and uniformly varied from a delicate minimum to a maximum over a wide range.

A further object is to provide means to 25 adjust the fuel supply independently of the mechanism above mentioned. While the above mechanism checks the flow of fuel as the air supply is throttled, it is desirable to provide improved means to adjust the 30 fuel supply independently to provide for variations in atmospheric conditions.

Other objects of the invention will appear 35 in the detailed description and annexed claims.

The embodiment of my invention chosen for the purpose of illustration is shown in the accompanying drawings.

Figure 1 is a side elevational view of my 40 improved carbureter, Fig. 2 is a sectional side elevation thereof, Fig. 3 is a sectional plan view taken on the line 3-3 of Fig. 1 and looking in the direction of the arrow, Fig. 4 is a sectional view of the fuel nozzle of my carbureter, and Fig. 5 is a dismembered perspective view illustrating the nozzle and the adjusting device therefor.

Referring to the drawings, *a* is the usual carbureter pipe casing, open to the air at the bottom and connected from the top by 50 pipe to the manifold of the engine in the common manner. Shutters or dampers *d* and *e*, rotatably mounted on transverse shafts *c* and *b*, respectively, swing within

pipe *a* and vary the supply of air, all in the ordinary manner. These dampers *d* and *e* 55 are connected by bell cranks *j* and *g* and link *i* to move in unison. The shaft *b* is also provided with an operating lever *f*, keyed to shaft *b* and rotatable between the stops *f'* to move the shutters *d* and *e*. So 60 far, what I have described is substantially old and is common practice in the art.

The novel features of my invention will now be described. Between the shafts *b* and *c* and parallel therewith, I provide a sleeve *l* 65 rotatably mounted in the wall of the pipe *a*. Fixed to the sleeve *l* is a bell crank *k* operated by a link *h* from the link *g* connected to lever *f*. The sleeve *l* is provided with a substantially triangularly shaped 70 notch or slot *l'*, widest at the end of the sleeve *l* and gradually tapering to a point as it nears the wall of pipe *a*. This slot is preferably cut with one edge parallel to the axis of the sleeve as shown and the other 75 edge in the form of a curve tapering toward and meeting the first edge at its inner end. Rotatably mounted in the wall of pipe *a* and within the sleeve *l* is a nozzle *m* and fixed to an extension of the latter is an operating lever *n*. The nozzle *m* is provided with a horizontal inlet hole *p* near the bottom thereof, and leading from hole *p* to the periphery of the nozzle *m* are a number of small vertical holes *q* which may be of various diameters. The nozzle *m* is mounted in suitable stuffing boxes to prevent leakage of the fuel, and a supply-pipe *o* communicates through a recess in the stuffing box to the hole *p* in the nozzle, as shown in 80 Fig. 3.

In operation, gasoline or other liquid fuel enters through the supply-pipe *o* into the hole *p* of nozzle *m* and issues from the apertures *q* in the form of spray. The jetting action is aided by the length of holes *q* forming the outlet for fuel from the inlet hole *p*. Assuming that the shutters *d* and *e* are wide open, to permit the maximum supply of air to the carbureter, then the sleeve *l* 95 is normally positioned on the nozzle *m* to allow the notch *l'* to register with all the apertures *q*. Thus, the maximum supply of fuel is obtained with the maximum amount of air. If, however, the lever *f* is moved to 100 throttle the air supply, by means of dam-

pers *d* and *e*, the sleeve *l* is rotated thereby, due to the connections *g*, *h*, and *k*. As the sleeve *l* turns, the notch *l'* passes out of registration with some of the apertures *q*, and 5 the fuel supply is decreased. A sufficient arc of rotation will finally close all but a single aperture *q*. It is to be noted particularly that only a very small angular movement of the sleeve is necessary to vary 10 the fuel supply from the minimum to the maximum. Furthermore, by the proper disposal of a sufficient number of apertures *q* the fuel may be made to vary uniformly and properly in proportion to the air supply.

15 To secure proper carburation, mechanism is preferably provided to vary the fuel supply, independently of the air supply, to provide for variations in atmospheric conditions. I obtain this result by moving the 20 operating lever *n*, thereby rotating the nozzle *m* relatively to the sleeve *l*. A certain number of apertures *q* may thus be closed even when the dampers *d* and *e* are set for the maximum air supply. This will de- 25 crease the richness of the mixture since the normal condition of the apparatus is adjusted to atmospheric conditions. By rotating the nozzle *m* in the opposite direction, a richer mixture may be obtained since a 30 certain number of apertures *q* will then remain uncovered by the sleeve *l* when the dampers are set for the minimum air supply. Thus, I have provided, in a carbureter, improved devices to vary the fuel intake in 35 proportion to the air intake. Furthermore, I have supplied improved mechanism to increase or decrease the richness of the mixture according to atmospheric or other conditions. Moreover, my invention comprises 40 a simple, easily-operable mechanism which is applicable to the ordinary carbureter and which provides a desired delicate adjustment of fuel throughout a wide range.

What I claim is—

- 45 1. In a carbureter, the combination with a casing, of means to vary the supply of air to said casing, a sleeve rotatable in said casing and operably connected with said means, said sleeve having a notched portion, 50 a nozzle extending into said sleeve and rotatable independently thereof, means to convey fuel to said nozzle, said nozzle having a plurality of apertures adapted to be successively opened by said sleeve.
- 55 2. A carbureter, having in combination, a mixing chamber, a fuel inlet means therefor, a series of separate openings from said means, a rotatable controlling device for said openings arranged to successively cover 60 and uncover said openings, an air inlet controlling means for the chamber operably connected to but otherwise independent of said device, and means successively to cover and uncover said openings without move- 65 ment of said rotatable controlling device.

3. A carbureter, having in combination, a mixing chamber, a fuel inlet means therefor, comprising a pipe member extending across the path of the air passing therethrough having a longitudinal fuel passage 70 at some distance from its top surface, and a series of small vertical passages leading from the longitudinal passage to the top surface, together with means to successively open and close said vertical passages as de- 75 sired, said means and said pipe being adjustable one with relation to the other so that a given movement of said means will open a more or less number of the vertical passages, and means, operable independently 80 of said first named means to successively open and close said vertical passages.

4. A carbureter, having in combination, a mixing chamber, a fuel inlet means therefor, comprising a cylindrical pipe member 85 extending transversely of the chamber having a longitudinal fuel passage at some distance from its top surface, and a series of small vertical passages leading from the longitudinal passage to the top surface, a 90 rotatable sleeve arranged to fit over said pipe member having a slot provided therein with one edge of the slot at an angle to the axis thereof, means to adjust the sleeve around the pipe member, whereby the vertical passages are successively opened and closed.

5. A carbureter, having in combination, a mixing chamber, a fuel inlet therefor, comprising, a cylindrical pipe member extending transversely of the chamber having a longitudinal fuel passage at some distance from its top surface and a series of small vertical passages leading from the longitudinal passage to the top surface, a rotatable sleeve arranged to fit over said pipe member and having a slot provided therein with one edge of the slot at an angle to the axis thereof, means to adjust the sleeve around the pipe member, whereby the vertical passages are successively opened and closed, means to adjust the pipe member with relation to said sleeve to determine the number of holes which a given movement of the sleeve will cover and uncover.

6. A carbureter, having in combination, a mixing chamber, distanced valves therein to control the passage of air therethrough, a fuel inlet arranged between said valves, comprising, a pipe extending transversely across the passage of the air through said chamber, a series of small openings extending from the upper surface of said pipe member through which fuel is adapted to be sprayed, a rotatable sleeve arranged to fit over said pipe member, having a slot therein, with one edge arranged at an angle to its axis, means to connect one of said air valves with said sleeve arranged so that the position of the air-valve will determine 120 125 130 135 140

the position of the sleeve, means to adjust the pipe member angularly with relation to the sleeve, all constructed and arranged so that a given movement of the air-
5 valve will open a given number of small openings in the pipe member, and the angular adjustment of the pipe member will de-

termine the number of openings uncovered by a given movement of said sleeve.
